UNITED STATES PATENT OFFICE.

JOHN OREN WEST, OF FULTON, KANSAS.

WIRE FENCE.

SPECIFICATION forming part of Letters Patent No. 308,024, dated November 11, 1884.

Application filed October 22, 1883. (No model.)

To all whom it may concern:

Be it known that I, JOHN O. WEST, a citizen of the United States, and a resident of Fulton, in the county of Bourbon and State 5 of Kansas, have invented certain new and useful Improvements in Wire Fences; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of my improved wire fence. Fig. 2 is a similar view 15 showing the fence under construction, and Figs. 3, 4, 5, and 6 are detail views.

Similar letters of reference indicate corresponding parts in all the figures. 20 My invention has relation to wire fences; and it consists in the improved construction and combination of parts of a fence having posts consisting of doubled rods straddling the fence, and provided with wires secured to their upper and 25 lower ends twisted around the several strands of wire, and having wires twisted around the several strands of wire and secured to posts or plugs in the ground, the former being placed at elevations of the ground, and the latter being 30 at the depressions of the ground in the line of the fence, as hereinafter more fully described and claimed.

In the accompanying drawings, the letters A indicate wooden blocks or plugs having 35 preferably spiral and tapering points and secured in the ground in pairs in the line of the fence. These blocks have a bore or recess, B, in their upper ends, and the ends of a doubled bent rod, C, are inserted into the recesses, 40 the rod straddling the fence-wires. The upper end of a wire, D, is secured to the upper doubled end of the post, is wrapped or twisted once around each wire strand E of the fence, and has its lower end hanging loose.

F indicates blocks or plugs of a construction similar to the base-plugs for the doubled posts, and the lower end of a wire, G, which is attached at its upper end to the uppermost strand of the fence and wound around each 50 strand, is secured to the upper end of the plug.

H indicates a corner post, which is of the same construction as the straddling posts, with

the exception that one leg is preferably vertical, or nearly so, while the other leg forms an inclined brace for the same, and the wire 55 strands are carried around the vertical leg, being spaced by means of a wire, I, secured to the upper doubled end of the post, wound around each strand of wire, and secured at its lower end to the base-plug of the vertical leg 60 of the post. Spacing-wires J are wrapped around the several strands of the fence in spaces between the posts, keeping the strands at their proper positions.

The fence is constructed by securing one 65 end of the lowermost strand to a rigid post, K, at its proper distance from the ground, from which post the strand is carried to another rigid post, resting at intervals at its proper distance from the ground upon pegs or 70 notches in the edges of a number of portable posts, L, having cross-pieces at their lower ends and placed upon the elevations in the line of the fence. The next strand is now placed in the notches of the portable posts at 75 its proper height, being secured at its ends to the rigid posts, &c.

For the purpose of spacing the wires at the intervals between the portable posts, bars M, having notches or pegs at their edges, are hung 80 upon the strands with their notches or pegs, and the base-plugs are now driven in, the posts placed in position, straddling the wires, the spacing-wires secured to the posts and wound around the strands, the anchoring-stakes driven 85 into the ground, and the anchoring-wires wound around the wire strands and secured to the stakes, and the intermediate spacing-wires wound around the wires, the straddling posts being placed upon the elevations of the ground 90 and the anchoring-wires being secured to the stakes at the depressions of the ground, the posts and their wires supporting and raising the strands, while the anchoring-wires draw the strands downward, the number of posts 95 being thus considerably reduced in comparison with fences having the wire strands secured exclusively to posts, consequently causing a saving in the space occupied by the fence and in the amount of material to be used. 100

Having thus described my invention, I claim and desire to secure by Letters Patent of the United States—

In a wire fence, the combination of the wire

strands, the posts consisting of doubled bars straddling the wire strands and placed at elevations of the ground, spacing-wires secured to the upper doubled ends of the posts and 5 wound around each strand of wire, and the anchoring-wires wound around each strand of wire, and secured at their lower ends to plugs or stakes in the ground at depressions of the same in the line of the fence, as and for the 10 purpose shown and set forth.

In testimony that I claim the foregoing as my own I have hereunto affixed my signature in presence of two witnesses.

JOHN OREN WEST.

Witnesses:

JOHN P. JOHNSTON,
CHARLES F. HARRAR.
